UNITED STATES PATENT OFFICE.

STEPHEN B. HAESSLY, OF FARIBAULT, MINNESOTA.

INTERNAL-COMBUSTION ENGINE.

1,327,384.

Specification of Letters Patent.

Patented Jan. 6, 1920.

Application filed April 21, 1916. Serial No. 92,623.

To all whom it may concern:

Be it known that I, STEPHEN B. HAESSLY, citizen of the United States, resident of Faribault, county of Rice, State of Minnesota, have invented certain new and useful Improvements in Internal-Combustion Engines, of which the following is a specification.

The object of my invention is to provide means whereby the heat in the engine cylinder resulting from the explosion of the gases therein may be utilized for vaporizing the fuel during its passage to the cylinder, and thereby the engine adapted for using a comparatively heavy oil, such as kerosene, as a fuel.

A further object is to provide a means for vaporizing the fuel when the engine is cold.

The invention consists generally in various constructions and combinations, all as hereinafter described and particularly pointed out in the claim.

In the accompanying drawings forming part of this specification,

Figure 1 is a plan sectional view of a gas engine cylinder with my invention applied thereto,

Fig. 2 is a vertical sectional view of the same,

In the drawing, 2 represents an engine cylinder having the usual jacket 3, piston 4 and connecting rod 5. The head 6 of the cylinder is provided with a port 7 and a valve 8, having a stem 9 provided with a spring 10 for normally holding the valve in its closed position, the valve being mounted to open automatically on the suction stroke of the piston to draw the gas into the explosion chamber, or its valve may be positively operated by the well-known mechanism employed for this purpose.

11 is a gas intake communicating with a passage 12 which extends around the valve 8 and has a port 13 leading to the valve. The intake 11 communicates with the carbureter and the supply of fuel and the kerosene mixture entering the passage 12 and contacting with the heated walls thereof will be vaporized and heated to a high degree and when discharged through the port 13 and the valve into the cylinder, will be at the desired temperature and state of vaporization for producing great efficiency in the operation of the engine. In other words, the heat of the engine is utilized for vaporizing the fuel and increasing the efficiency

of the charge. This passage in the cylinder head may be varied in length and in cross sectional area according to the size of the cylinder and the charge of gas to be delivered. In this way I am able to use a heavy oil, such as kerosene, for fuel with good results.

The air, with the kerosene held in suspension, will enter the passage in the head and will flow in opposite directions therein, and be retarded by the mixing of the oppositely flowing currents, and the kerosene contacting with the heated walls of the passage will be vaporized and this vaporization will be continuous and the mixture made more complete when the currents of air meet in the passage at the point where they flow through the valve to the engine cylinder.

I have found by actual test that kerosene can be vaporized and successfully used in an internal combustion engine by passing it through the duct in the heated head of the cylinder before delivery to the combustion chamber. The air, of course, entering this passage will be carbureted, but the oil will not become vaporized until heated and as soon as the cylinder has become hot, the duct in the head will radiate sufficient heat to vaporize the kerosene without the assistance of any outside agency.

In starting the engine when the cylinder is cold, I prefer to provide a plate 14, preferably of copper, mounted on legs 14' by means of screws 15. A plug 16 is mounted in the cylinder head and insulated therefrom and has a terminal 17 for connection to an electric current and to the plate 14 so that when a current from some suitable source is passed through the terminal 17 the legs will offer sufficient resistance to the flow of the current to the heat to cause the soft copper plate to become heated, and this plate is located in the path of the carbureted air entering through the valve 8. When the globules of oil held in suspension by this air contact with this hot plate, they will become vaporized and will form a gas charge to be ignited in the cylinder. As soon as the walls of the duct become heated sufficiently to vaporize the oil, the electric current may be turned off. At all times, however, this copper plate in the path of the vapor operates as a spreader to mix and diffuse the vapor as it enters the combustion chamber. I am thus able to utilize an oil, such as kerosene, under all conditions of the engine; that is

- in first starting it and after it has been used for a time and the walls of the cylinder become heated. When the walls of the cylinder and the plate become heated, the current 5 may be cut off from the plate and during the operation of the engine the vapor entering the combustion chamber will contact with the plate and be more thoroughly vaporized before ignition.
- 10 I provide an exhaust passage 18 communicating with the cylinder and with the valve 19 through which the burned gases are discharged on the scavenging stroke of the piston. The water circulation for the cylinder 15 is preferably arranged so that it does not pass through the cavity in the head adjacent to the walls of the vaporizing duct, as this circulation would have a tendency to reduce the temperature of these walls and this, of course, is to be avoided.

20 In various ways the details of construction

herein shown and described may be modified and still be within the scope of my invention.

I claim as my invention:

25 An internal combustion engine comprising a cylinder having its head provided with a gas intake port and a centrally mounted valve therefor, said head having a vaporizing duct formed in its walls extending entirely around said valve and said duct having a port communicating through said valve with the combustion chamber, and a duct on the other side of said valve for connection with the carbureter, the charge 30 entering said duct flowing in opposite directions therein around said valve and being retarded by the mixing of the oppositely flowing currents.

35 In witness whereof I have hereunto set 40 my hand this 18th day of April, 1916.

STEPHEN B. HAESSLY.
